CLAIM

The ornamental design for an autonomous lawn mower, as shown and described.

DESCRIPTION

FIG. 1 is a perspective view of an autonomous lawn mower showing our new design;

FIG. 2 is a front view of the design shown in FIG. 1;

FIG. 3 is a rear view of the design shown in FIG. 1;

FIG. 4 is a left side view of the design shown in FIG. 1;

FIG. 5 is a right side view of the design shown in FIG. 1;

FIG. 6 is a top view of the design shown in FIG. 1; and,

FIG. 7 is a bottom view of the design shown in FIG. 1.

Portions of the autonomous lawn mower shown in broken lines in given embodiment(s) form no part of the claimed design.
